Bonney, U.S. Appl. No. 29/471,083, filed Oct. 28, 2013, entitled "Hearing Protector".

Primary Examiner — Elizabeth J Oswecki

(74) Attorney, Agent, or Firm — Irina Hass

(57) **CLAIM**

The ornamental design for a hearing protector, as shown and described.

DESCRIPTION

FIG. 1 is a perspective view of a hearing protector showing our new design;

FIG. 2 is a right side view thereof;

FIG. 3 is a left side view thereof;

FIG. 4 is a front view thereof;

FIG. 5 is a rear view thereof;

FIG. 6 is a top view thereof; and,

FIG. 7 is a bottom view thereof.

The portions of the hearing protector in FIGS. 1-7 shown in broken lines are included to show features that form no part of the claimed design.
